UNITED STATES PATENT OFFICE.

LILLIAN GRAHAM, OF PHILADELPHIA, PENNSYLVANIA.

DESIGN FOR A SCOURING DEVICE.

48,441.

Specification for Design.

Patented Jan. 11, 1916.

Application filed October 26, 1915. Serial No. 58,083. Term of patent 7 years.

To all whom it may concern:

Be it known that I, LILLIAN GRAHAM, a citizen of the United States, residing at Philadelphia, in the county of Philadelphia and State of Pennsylvania, have invented a new, original, and ornamental Design for Scouring Devices, of which the following is a specification, reference being had to the accompanying drawing, forming a part thereof.

The figure is a view in elevation of a scouring device, showing my new design.

I claim:

The ornamental design for a scouring device, as shown.

LILLIAN GRAHAM.
